UNITED STATES PATENT OFFICE.

IRA B. MALABY, OF PHILADELPHIA, PENNSYLVANIA, ASSSIGNOR TO NORMAN MELLOR, OF PHILADELPHIA, PENNSYLVANIA.

WALL-ANCHOR.

1,111,660.

Specification of Letters Patent. Patented Sept. 22, 1914.

Application filed June 16, 1913. Serial No. 774,009.

To all whom it may concern:

Be it known that I, IRA B. MALABY, a citizen of the United States, residing in Philadelphia, Pennsylvania, have invented 5 certain Improvements in Wall-Anchors, of which the following is a specification.

One object of my invention is to provide a novel form of expansible holding device commonly known as a wall anchor which 10 shall be particularly adapted for the support of relatively heavy structures; it being also desired that the device shall be inexpensive to make and convenient to use. These objects and other advantageous ends 15 I secure as hereinafter set forth, reference being had to the accompanying drawings, in which,

Figure 1 is a side elevation of one form of my invention; Fig. 2 is a plan of the wall 20 anchor shown in Fig. 1; Fig. 3 is a plan of the blank from which the body of the wall anchor is made; Figs. 4 and 5 are side elevations, partly in section, illustrating my invention in position ready for expansion, and 25 in the form assumed after expansion, respectively; Fig. 6 is an elevation of a modified form of my invention, and Fig. 7 is an elevation partly in section illustrating a special 30 form of my invention applied to support an eyebolt.

Referring to the above drawings, 1 represents the blank of which the wall anchor comprising my invention is preferably formed; this being made of a body of sheet 35 metal, usually steel, of the requisite thickness and so formed as to have a series of elongated projections or fingers 2, extending from one of its edges. The blank is also provided with a number of transversely 40 elongated holes 3 in its body portion, and by suitable machinery is rolled up into an approximately cylindrical form so that the fingers 2 project at one end. A nut 4 of suitable dimensions is mounted so as to be 45 encircled by said fingers, being put in place either before the blank is rolled up or after this operation, and said fingers may thereafter be bent inwardly as indicated at 5, so as to support the nut some distance away 50 from the body portion of the blank. They may also be turned over at their ends as indicated at 6, to prevent the removal of the nut, although if desired the latter may be seated upon the end of the body portion as shown 55 in Fig. 6, with its corners projecting between

the various fingers 2, which in this case may be provided with an integral strip 7 joining their outer ends so as to hold the nut in place.

In using such a wall anchor as shown in 60 either Figs. 1 or 7, there is first formed a substantially cylindrical hole 8 in the wall or other structure 9 in which the wall anchor is inserted. After mounting a jam nut 11 and a washer 12 on a bolt 10, the 65 threaded end of the latter is entered in the nut 4, and after said bolt has been screwed partly or wholly through this nut, it is held from further rotation by its head 13 while the jam nut 11 is turned by a suitable 70 wrench so as to draw the nut 4 toward said head. As a result, the structurally weak portions 14, lying between the openings 3, are caused to bulge outwardly as the nut 4 is drawn toward the nut 11 and their more 75 or less sharp projecting portions 15 tightly grip or are forced into the walls of the cavity 8, thereby holding the wall anchor firmly and immovably in place. Thereafter the bolt 10 may be removed merely by unscrewing it from engagement with the nut 4 and a bolt having threads of the proper pitch may be screwed into the socket provided by this wall anchor so as to support any desired 80 structure such as the angle iron 17 shown in 85 Fig. 5.

If desired, the washer 12 and jam nut 11 may be mounted on a bolt which is to permanently remain in engagement with the wall anchor, and said bolt, as shown in Fig. 90 7, may be itself used as the expanding tool. In this case, the eye bolt 18, after being entered in the nut 4, may be held from turning by a suitable bar and thereafter the jam nut 11 may be turned up so as to cause the 95 structurally weak side members 14 to be bulged outwardly into holding engagement with the walls of the cavity 8 in the masonry or other structure 9.

I claim:

1. The combination in a wall anchor of a body of sheet metal in substantially cylindrical form, having apertures in its sides and projecting fingers at one end; with a nut embraced and immovably held by said 105 fingers, the corners of the nut entering the spaces between the fingers and the latter being bent over at least one face of said nut.

2. The combination in a wall anchor of a body of sheet metal in substantially cylindri- 110

- cal form, having apertures in its sides and projecting fingers at one end; with a nut embraced and immovably held by said fingers; there being portions of the fingers extending over the nut to hold it in place.
3. An expandible wall anchor consisting of a tubular body having elongated apertures in its sides forming structurally weak side members, and a series of fingers projecting from one end; with a nut inclosed by said fingers and mounted with its corners projecting between the same; said nut being seated on the adjacent end of the body portion and having parts of the fingers extending over it.
4. The combination in a wall anchor of a

tubular body portion of sheet metal having elongated side openings providing structurally weak side members; a series of fingers projecting from one end of the body portion and having their outer ends connected together to provide a series of openings; with a nut embraced by said fingers and having its corners projecting in said openings.

In testimony whereof, I have signed my name to this specification, in the presence of two subscribing witnesses.

IRA B. MALABY.
